SAFETY PARACHUTE DEVICE FOR AEROPLANES

Filed March 15. 1929

UNITED STATES PATENT OFFICE

VINCENZO PELLEGRINO, OF RYE, NEW YORK

SAFETY PARACHUTE DEVICE FOR AEROPLANES

Application filed March 15, 1929. Serial No. 347,227.

This invention relates generally to new and useful improvements in aeroplanes and has more particular reference to an aeroplane provided with a plurality of parachutes capable of supporting the plane in the event of an emergency.

The invention has for an object the provision of a device of the class mentioned which is of simple durable construction, dependable in use and efficient to action, and which can be manufactured and sold at a reasonable cost.

The invention proposes the use of a plurality of parachutes connected by cables to various parts of the aeroplane, and normally stored in chambers within the plane, said chambers being closed by doors held by latching means releasable to permit ejecting means to eject the parachute from the chambers.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:—

Fig. 1 is a perspective view of an aeroplane constructed according to this invention.

Fig. 2 is a fragmentary enlarged plan detail view of a portion of Fig. 1.

Fig. 3 is a fragmentary elevational view looking in the direction of the arrows 3—3 of Fig. 2.

Fig. 4 is a horizontal sectional view of one of the storage chambers.

Fig. 5 is a view similar to Fig. 4 but showing the ejecting means in extended position.

Fig. 6 is a similar view to Fig. 4, showing a modified form storage chamber.

The reference numeral 10 indicates generally an aeroplane having main wings 11 and a pilot's chamber 12. A plurality of parachutes 13 are connected by cables 14 to various points on the tops of the wings 11. These cables are of groups of different lengths so that the parachutes assume various heights in which they may expand and not in-

terfere with each other. The wings 11 are provided with storage chambers 15, one for each parachute and preferably arranged with an opening communicating with the edge of the wings. This is not intended as a limitation since the chambers could just as well communicate with the top surface of the wings. Dot and dash lines 16 indicate the position of the cables 14 when the parachutes are disposed within the storage chambers. As shown in Fig. 1 the parachutes are in positions for supporting the aeroplane.

Each of the storage chambers is provided with a pivoted door 17, and latching means 18 are mounted on the wings 11 and arranged for latching the doors in closed positions. A branch cable 19 connects with each of the latching means and is guided over pulleys 20 mounted on the wings, and connect with a master cord 21 terminating in the vicinity of the pilot's chamber 12. The free end of the master cord passes thru a standard 22 fixed upon the wings 11, and a handle 23 is secured upon this free end and may be conveniently reached by a pilot within the chamber 12. Each of the storage chambers is provided with an ejecting means 24 shown in detail in Figs. 4 and 5.

Each of the latches 18 consists of a bar 25 pivotally mounted intermediate of its ends upon a post 26 projecting from a wing 11, and said post has an inclined top as indicated by reference numeral 27 so that when the bar 18 pivots, it moves in an inclined plane with respect to the horizontal. One end of the bar 18 is provided with a latching finger 28 adapted for engaging against the door 17 and holding the door in a latched position. The tension spring 29 is connected between the other end of the bar 25 and the wing 11 for urging the latching finger into its latching position. The branch cable 19 connects with the end of the bar, remote from the latch finger 28.

Each of the ejecting means contained in the chambers 15 consists of a transverse platform 30 having inwardly projecting stop arms 31 with offset ends 32 arranged for engaging the ends of a plurality of openings 33 in the wing for limiting the outward motion of the platform to a position substantially

aligned with the outer edge of the wing. Coaxial expansion springs 34 are arranged upon the stop arms 31 and act between the platform and the inner face of the chamber 5 for normally urging the platform outwards to its extended position.

Side members 35 hingedly connect with the edges of the platform 30, and coaxial springs 36 are mounted on the hinged points 10 for normally urging the side members outwards to a position in the same plane as the plane of the platform. In Fig. 4 numeral 37 indicates a parachute in a folded condition within the storage chamber 15, while the 15 storage chamber is closed.

The door 17 of the chamber is hinged as at 38 and the parachute indicated by numeral 37 rests between the door 17, the platform 30, and the side members 35. In an extended position of the platform as shown in Fig. 5, 20 one of the side members indicated by reference numeral 35' abuts against the hinge 38 of the door 17 and locks the door in an open position against closing, so that the door may 25 not accidentally swing closed and the chamber contain no parachute, with the operator of the machine not knowing this condition.

In operation of the device, while the aeroplane is in flight, and in case of emergency, 30 the pilot draws the handle 23 for releasing all of the latches 18. Immediately the expansion springs 35 push forwards on the platforms 30 forcing the doors 17 open and ejecting the parachutes 13 from the storage chambers. These parachutes assume the positions 35 illustrated in Fig. 1 and serve to support the machine.

In Fig. 6 I have shown the storage chamber 15 curved near the door 17 as shown at 15' 40 to guide the parachute 13 to the surface of the wing or body. Springs 34' may be of different size to allow a longer expansion during the curved path of the platform 30.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. In an aeroplane, wings formed with parachute storage chambers, doors normally closing the chambers, latches for holding the doors closed, ejecting means within each chamber for ejecting a parachute automatically upon the opening of the door, and a 55 means for disengaging the latches, said ejecting means consisting of platforms arranged to move within the chambers and urged outwards by springs and arrested in fully extended positions by stop arms, and side members pivoted on the platforms and urged out-

wards by springs so as to assume positions in the same plane as the platforms in the extended position of the platforms.

2. In an aeroplane, wings formed with parachute storage chambers, doors normally closing the chambers, latches for holding the doors closed, ejecting means within each chamber for ejecting a parachute automatically upon the opening of the door, and a means for disengaging the latches, said ejecting means consisting of platforms arranged to move within the chambers and urged outwards by springs and arrested in fully extended positions by stop arms, and side members pivoted on the platforms and urged outwards by springs so as to assume positions in the same plane as the platforms in the extended position of the platforms, 70 said stop arms projecting from the rear side of the platforms and engaging in openings in said wings and formed with offset ends arranged for engaging the ends of said openings.

3. In an aeroplane, wings formed with parachute storage chambers, doors normally closing the chambers, latches for holding the doors closed, ejecting means within each chamber for ejecting a parachute automatically upon the opening of the door, and a means for disengaging the latches, said ejecting means consisting of platforms arranged to move within the chambers and urged outwards by springs and arrested in fully extended positions by stop arms, and side members pivoted on the platforms and urged outwards by springs so as to assume positions in the same plane as the platforms in the extended position of the platforms, 75 said stop arms projecting from the rear side of the platforms and engaging in openings in said wings and formed with offset ends arranged for engaging the ends of said openings, 80 and the springs for ejecting the platforms being coaxially mounted on said stop arms.

4. In an aeroplane, wings formed with parachute storage chambers, doors normally closing the chambers, latches for holding the doors closed, ejecting means within each chamber for ejecting a parachute automatically upon the opening of the door, and a means for disengaging the latches, said ejecting means consisting of platforms arranged to move within the chambers and urged outwards by springs and arrested in fully extended positions by stop arms, and side members pivoted on the platforms and urged outwards so as to assume positions in the same plane as the platforms in the extended position of the platforms, 95 springs being coaxially mounted on the hinge points of said side members for accomplishing the outward urging 100 of the side members.

In testimony whereof I have affixed my signature.

VINCENZO PELLEGRINO.
